PRECISION INTERNAL THREAD GAUGE

George E. Mock, Phoenix, Ariz., assignor to
Osborn Products, Inc., Phoenix, Ariz.

Filed Sept. 1, 1970, Ser. No. 24,792

Term of patent 14 years

Int. Cl. D10—04

U.S. Cl. D52—6

FIG. 1 is a front perspective view of a precision internal thread gauge showing my new design;

FIG. 2 is a front view of FIG. 1; and

FIG. 3 is a back perspective view of FIG. 1.

I claim:

The ornamental design for a precision internal thread gauge, as shown.
